Primary Examiner — Catherine Ho

(57) **CLAIM**

The ornamental design for a combined sign frame with detachable sign, as shown and described.

DESCRIPTION

FIG. 1 is a perspective view of the sign frame portion of the combined sign frame with detachable sign, isolated for clarity of disclosure.

FIG. 2 is a front elevational view thereof, the back elevational view being an identical image thereof.

FIG. 3 is a side elevational view thereof, the opposite side view being an identical image thereof.

FIG. 4 is a top plan view thereof.

FIG. 5 is a bottom plan view thereof.

FIG. 6 is a perspective view of a combined sign frame with detachable sign.

FIG. 7 is a front elevational view thereof, the back elevational view being an identical image thereof.

FIG. 8 is a side elevational view thereof, the opposite side view being an identical image thereof.

FIG. 9 is a top plan view thereof; and,

FIG. 10 is a bottom plan view thereof.

1 Claim, 6 Drawing Sheets
